(57) CLAIM

The ornamental design for a vent panel, as shown and described.

DESCRIPTION

FIG. 1 is a front perspective view depicting a vent panel; FIG. 2 is a front elevation view depicting the vent panel of FIG. 1; FIG. 3 is a rear elevation view depicting the vent panel of FIG. 1; FIG. 4 is a right side elevation view depicting the vent panel of FIG. 1; FIG. 5 is a left side elevation view depicting the vent panel of FIG. 1; FIG. 6 is a top plan view depicting the vent panel of FIG. 1; and, FIG. 7 is a bottom plan view depicting the vent panel of FIG. 1.

The broken lines depict portions of the vent panel that form no part of the claimed design. The dot dash broken lines denote the boundaries of the claim and form no part thereof.
